UNITED STATES PATENT OFFICE.

PETER SOMMER, JOHN SOMMER, AND PETER W. SOMMER, OF TREMONT, ILLINOIS.

WIRE-STRETCHER.

SPECIFICATION forming part of Letters Patent No. 566,030, dated August 18, 1896.

Application filed January 19, 1895. Serial No. 535,487. (No model.)

To all whom it may concern:

Be it known that we, PETER SOMMER, JOHN SOMMER, and PETER W. SOMMER, citizens of the United States, residing at Tremont, in the county of Tazewell and State of Illinois, have invented certain new and useful Improvements in Wire-Stretchers; and we do hereby declare that the following is a full, clear, and exact description of the invention, which will enable others skilled in the art to which it app pertains to make and use the same.

Our invention relates to certain new and useful improvements in wire-stretchers by means of which a simple stretcher is provided, being very efficient for the purpose designed.

More particularly, our invention relates to a stretcher purposed to engage a single wire for the purpose of taking up the slack therein, a series of said stretchers being employed for taking up the slack in a fabric in which a series of horizontal parallel line-wires are used, but each stretcher is operated independently and by separate means to draw up each longitudinal wire of the fabric.

Our invention consists, essentially, of a general frame part or standard, of a spindle suitably journaled to turn within the said standard and provided with projecting rims bearing between the parts of the standard that support the journals of said spindle and provide a sort of spool in conjunction with the spindle to facilitate in the winding of the wire upon the said spindle, one of the said rims being somewhat larger in circumference than the other and having the periphery thereof formed with ratchet-teeth, making, substantially, a ratchet-wheel of the said rim, an engaging link suitably pivoted in connection with the standard-framework and bearing in such position with relation to the said ratchet-teeth upon the said rim as to traverse the separate teeth thereof when the spindle is being turned to draw up the wire and to engage the same to prevent backward turning when such winding of the said spindle is stopped, and of certain other details of construction hereinafter more particularly explained.

That our invention may be more fully understood, reference is had to the accompanying drawings, in which—

Figure 1 shows an elevation of our improved

stretcher. Fig. 2 is a side view of the same. Fig. 3 is a horizontal cross-section showing details of the spindle and standard. Fig. 4 shows the particular application of the stretcher for 55 operation.

In the figures, A refers to the general framework or standard, the base thereof being open and constructed substantially in a rectangular form and with a portion of the sides 60 thereof bearing upwardly and being properly recessed to provide bearings for the spindle.

B is a spindle, which may be constructed with the central body perforated, as at d, to provide for the passage of the end of a wire 65 therethrough.

C is a rim extension from the spindle. D is also a rim extension from the said spindle. The said rims, as shown, bear between the sides of the standard and provide such bearings as will prevent lateral movement of the spindle, and also provide, in conjunction with the body of the spindle, a sort of spool, between the rims of which and upon the central body portion thereof is designed to be wound 70 a wire strand connected with the spindle by having the end thereof passed through the perforation d therein and then wrapped around the said spindle as it is turned. 75

The rim D is somewhat larger than rim C, 80 and the periphery thereof is formed with ratchet-teeth thereon, as shown in the drawings.

a is a link which may be formed of a short piece of ordinary wire and is purposed to be 85 carried in connection with the standard-framework in such a manner as to accommodate the free movement of the upper portion of the said link, its connection with the standard being practically pivotal, it being pur 90 posed that said link shall be connected with the stretcher-framework at the point, as shown in the drawings, just above the ratchet-wheel D of the spindle and in such a manner that the gravitating tendency thereof, 95 when free to move, will cause the upper portion of the said link to bear upon the top edge of a portion of the standard-framework upon one side of the ratchet-wheel and upon the lug extension c on the opposite side of 100 the said ratchet-wheel and the portion of the link between the said points engaging the

ratchet-wheel, the relation between the said link and ratchet-wheel being such that when the spindle is turned to wind up the wire thereon the said link will traverse the surface 5 of the wheel moving freely up and down over the ratchet-teeth and when the winding of the spindle ceases will engage the said ratchet-teeth or the one immediately adjacent to the link to prevent backward turning of the 10 spindle.

The manner of securing the stretcher to the post is particularly illustrated in Fig. 4, the upper portion of the said figure showing a cut section of a post revealing a transverse 15 opening therethrough for the passage of the wire, it being purposed that the said stretcher shall be set so that the spindle thereof shall be on a line with the said opening and that the stretcher-framework shall be secured to 20 the post by means of a screw or other suitable means, the lower portion of the figure illustrating the manner of turning of the spindle, the direction of such turning, and the manner of the engagement of the ratchet- 25 wheel by the link.

The application of the device for practical use is very simple. When applied for stretching a single strand, the connection of the wire with the stretcher-spindle is made, in the 30 manner as previously explained, by passing the end thereof through the perforation *d* therein and bending it in such a manner as to provide a firm connection thereof with the said spindle. Then by attaching the 35 crank provided for connection with the said spindle and turning the same the wire will be wrapped around the said spindle, this operation being continued until the wire is drawn with sufficient tension or the tension 40 desired.

When the stretcher is used in connection with a fencing fabric in which there are employed a series of horizontally parallel line-wires, a series of said stretchers must be used, 45 one with each of the said wires, the connec-

tion with the stretcher and the operation for drawing up the wire being the same as above described. All of the stretchers being located upon the same post and at intervals apart corresponding with the intervals between the 50 strands of the fabric being drawn up, and all of the strands are drawn up and held under sufficient tension to cause the same to bear practically in a horizontal line, which position of the fabric will be maintained as the spindles 55 of the stretchers are held securely from backward turning, and any relaxation in the fabric or sagging therein, occasioned by expansion of the material and attendant lengthening of the strands of the fabric, may be readily taken up by simply giving the spindle of each stretcher a few turns.

Having thus fully described our invention, what we claim, and desire to secure by Letters Patent, is—

In a wire-strand stretcher, the combination with the base *A*, having a large opening in the bottom thereof and provided with the openings in the standard or side pieces to receive the spindle and with the lug *c*, of the spindle 70 *B*, having the perforation *d* therein and provided with small rim *C* and a large rim *D*, having the peripheral ratchets, and the partial link *a*, bearing across the full width of the base and pivoted in the sides of the base 75 in such a manner that it will swing so as to bear upon the edges of the base and the lug *c* thereon and engage the ratchets on rim *D*, and so that it may swing clear of the ratchet-teeth, all substantially as described and 80 shown.

In testimony whereof we affix our signatures in presence of two witnesses.

PETER SOMMER.

JOHN SOMMER.

PETER W. SOMMER.
